UNITED STATES PATENT OFFICE.

ZACHARY T. CARROLL, OF ST. LOUIS, MISSOURI.

VELOCIPED.

No. 838,381.

Specification of Letters Patent.

Patented Dec. 11, 1906.

Application filed February 17, 1906. Serial No. 301,629.

To all whom it may concern:

Be it known that I, ZACHARY TAYLOR CARROLL, a citizen of the United States, and a resident of St. Louis, Missouri, have invented 5 certain new and useful Improvements in Velocipedes, of which the following is a specification.

My invention is an improvement in velocipedes, and particularly in combined rocking-horses and velocipedes; and the invention 10 has for an object to provide a novel construction whereby the figure of the horse may be caused to simulate a galloping action as the velocipede moves forward; and the invention 15 consists in certain novel constructions and combinations of parts, as will be hereinafter described and claimed.

In the drawings, Figure 1 is a sectional side elevation of a toy embodying my invention. Fig. 2 is a detail rear elevation of the 20 frame and a part of the running-gear. Fig. 3 is a detail cross-section on about line 3-3 of Fig. 1; and Fig. 4 is a detail side view of a portion of the figure of the horse, showing the 25 fixed relation between the drive-shaft and the saddle.

As shown, my invention is embodied in a tricycle having a front wheel A and rear wheels B, the latter being fixed to the shaft 30 C, which shaft is provided with a crank C' and with a sprocket-wheel C² for purposes presently described. The shaft C is mounted in bearings at D', in what for convenience of reference I call a "main frame" D, which 35 has an upwardly-projecting portion D². This upwardly-projecting portion is provided at its upper end with the longitudinally-extending side bars d, which extend approximately parallel with each other, are spaced 40 apart, receive between them the intermediate gearing between the drive-shaft and the drive-axle, and are provided at their opposite sides with the laterally-projecting pivot-studs D³ for the figure-body. This construction 45 is important, as it affords ample space between the side bars for the intermediate gearing and supports the pivot-studs at such distance apart as to afford a strong substantial pivotal support for the body, the arrangement being such as to obviate twisting strain 50 on the pivot and to provide a maximum strength. These studs D³ project laterally from the opposite side portions d, and between the bars d I provide a sprocket-wheel F 55 D⁴, which is connected by a sprocket-chain F with the sprocket-wheel C² on the shaft C.

On the studs D³ is pivoted the body E of the horse. To the wheel D⁴ is connected a larger sprocket-wheel D⁵, which is driven in the manner presently described. The figure E 60 of the horse has a saddle at E', is provided in advance thereof with an opening E², through which the steering-shaft G projects, and the figure of the horse is pivoted on the studs D³, so it may be rocked as the velocipede proceeds, it being forced to rock by means of the pitman H, connecting the crank C' with the body E at e, as shown in Fig. 1. By this construction when the shaft C is turned its crank C' will cause the figure E to rock on its 70 pivots D³, and so simulate the action of galloping as the velocipede moves forward.

It is important to maintain the fixed relation between the saddle E' and the drive-shaft I, by which the rider gives motion to 75 the velocipede, and to this end I journal the drive-shaft I in the figure of the horse, preferably near the lower edge of the latter, so that there will be no variation in distance between the saddle and the drive-shaft as the velocipede moves forward. I therefore journal the shaft I, which has the cranks I' at its opposite ends, in the body and preferably in metal bearing-plates J, secured at the sides of the 80 body, and provide the said shaft within the body with a sprocket-wheel i, geared by the chain K with the sprocket-wheel D⁵, so that the rider may transmit motion through the shaft I to the sprocket-wheel C² and its shaft C to propel the velocipede as the rider turns 90 the shaft I.

It will be understood that the counter-wheels D⁴ and D⁵ are concentric with the pivot of the figure-body E of the main frame of the velocipede, so that there will be no 95 variation in distance between the centers of the wheels D⁴ and D⁵ and the shaft I and the chain K will remain at the desired tension.

An important feature of my invention, as before suggested, is the arrangement of the 100 shaft I in fixed relation to the saddle E', so that the reach of the rider will not be disturbed at any time, this being effected by journaling the drive-shaft in the body to which the saddle is fixed so that the relation 105 of the said parts remains constant.

It will be noticed that the slot E² for the steering-shaft extends rearwardly for a considerable distance and receives the upper portion of the main frame of the velocipede 110 as well as the connection at e of the pitman H with the body, the slot being covered for

a short distance in front and rear of the saddle E' by a cloth or flexible cover, as shown in Figs. 1 and 4. This is a simple construction and facilitates the manufacture of the 5 article at a minimum cost.

It will be noticed that the steering-shaft extends upwardly through the longitudinally-slotted body, the slot of the latter permitting the rocking of the body along the rigid 10 shaft and avoiding the necessity of any links or other connections that might be necessary in the use of a steering-shaft which rocked with the figure-body. This is also important as affording additional exercising means, as 15 in the rocking of the body the saddle approaches and recedes from the steering-handles, as will be understood by reference to Fig. 1 of the drawings.

Having thus described my invention, what 20 I claim as new, and desire to secure by Letters Patent, is—

1. The improvement in velocipedes herein described, comprising the main frame having a steering-wheel at its front end, drive-wheels 25 and an axle therefor at its rear end, said axle being provided with a crank and a sprocket-wheel, the main frame having an upwardly-projecting portion provided at its upper end with laterally-projecting pivot-studs and between 30 said studs with sprocket-wheels concentric with the pivot-studs, and a body or figure slotted longitudinally receiving the upper portion of the main frame and having bearings for the lateral pivot-studs and above 35 the same a saddle, and a drive-shaft journaled in the figure-body and maintained in fixed relation with the saddle whereby the reach of the rider will not vary as the figure rocks on its pivots, said drive-shaft being 40 provided with cranks, gearing between the said drive-shaft and the sprocket-wheels concentric with the pivot-studs for the figure-body, and a pitman connecting the crank of the axle with the figure-body whereby to 45 rock the same on its pivots, substantially as set forth.

2. The combination in a velocipede of the main frame, the axle journaled thereto and having a crank, and drive-wheels on said axle, 50 a figure-body having a saddle and pivoted to the main frame, gearing concentric with said pivot and connected with the axle to drive the same, and a drive-shaft journaled to the figure-body in fixed relation to the saddle 55 thereof and having cranks, gearing between said shaft and the counter-gearing connected with the axle, and a pitman connecting the axle-crank with the figure-body, substantially as set forth.

60 3. The combination of the main frame having a drive-axle, a figure-body pivoted to the main frame and having a saddle, a drive-shaft journaled in the figure-body and main-

taining a fixed relation to the saddle, means for rocking the body on its pivot by the operation of the velocipede, and connections 65 between the drive-shaft and the drive-axle whereby the former will operate the latter, substantially as set forth.

4. The combination in a velocipede of the frame, the drive-axle, the upwardly-projecting steering-shaft, the figure-body pivoted to the main frame and slotted longitudinally for the play of said body along the steering-shaft as the body rocks, a drive-shaft journaled to 75 the figure-body whereby its relation thereto is unchanging, means for rocking the figure-body by the operation of the velocipede, and intermediate gearing between the drive-axle and the drive-shaft, substantially as set 80 forth.

5. In a device of the class described, the combination of the figure-body having a slot formed in its lower side and a main frame having 85 its upper portion in said slot and having at said upper portion longitudinal parallel side bars spaced apart, pivotal connections between the said opposing side bars and the figure-body, gearing between said side bars, the drive-axle, means connecting the drive- 90 axle with said gearing between the side bars and the drive-shaft journaled to the figure-body, and connected with the gearing between the side bars to operate the same, substantially as set forth.

95 6. The combination of the velocipede-frame and its drive-axle, a figure-body pivoted to the frame, means for rocking said body by the operation of the velocipede, a drive-shaft journaled to the body whereby its relation thereto is constant, and intermediate 100 gearing between said drive-shaft and the drive-axle of the velocipede, substantially as set forth.

7. The combination of a support, a figure- 105 body pivoted to oscillate on said support, and means for oscillating the figure-body including a drive device having a fixed relation to the body whereby its position with respect thereto will be constant while operating to 110 oscillate the body, substantially as set forth.

8. The combination of the velocipede-frame and its drive-axle, a figure-body pivoted to said frame, means for oscillating the body by the operation of the velocipede, a 115 drive device supported directly by the figure-body whereby its relation thereto will be constant in the operation of the velocipede to rock or oscillate the figure-body, and intermediate connections between the said drive 120 device and the drive-axle of the velocipede, substantially as set forth.
